OR D 13,538

No. 13,538

JAN 23, 1883

UNITED STATES PATENT OFFICE.

HENRY BOSSHARDT, OF NEW YORK, N. Y., ASSIGNOR TO THE KURSHEEDT MANUFACTURING COMPANY, OF SAME PLACE.

DESIGN FOR EMBROIDERY.

SPECIFICATION forming part of Design No. 13,538, dated January 23, 1883.

Application filed September 28, 1882. Term of patent 7 years.

To all whom it may concern:

Be it known that I, HENRY BOSSHARDT, of New York, in the county and State of New York, have invented a new and original Design for an Embroidery, of which the following is a specification.

The accompanying photograph represents a face view of my new embroidery.

This invention relates to a new embroidery representing a cockatoo; and it consists of the new configuration, and also of the new ornamentation thereof.

In the drawing, the letter A represents the head of the embroidered cockatoo. B is the body thereof, and C the tail.

The head A has the representation of the eye of the animal, and around the same, in spiral lines, representations of the crown-feathers a, and in front the representation of a bill, b.

The body B is composed of two main series, d and e, of representations of body-feathers, showing at f a portion of the belly, and the part d is partially overlapped by representations g of the feathers on the back. The wing-

feathers h extend backward from the portion e. The talons i extend forward from the body B, as shown.

The tail C is composed of series of representations of tail-feathers that separate at the lower end.

The whole arrangement of these portions a b d e f g h i, together with the tail C, produces a peculiar effect upon the eye, and this effect is increased by the direction of the embroidery-threads in the representation of each feather, namely: The embroidery-threads extend diagonally or obliquely across the breadth of each feather from one edge to the other thereof, and are not true representations in that respect of the appearance of a genuine feather, inasmuch as the central vein is missing and the diverging lines from the vein are omitted. Thus the effect is heightened as to the peculiarity of the design.

I claim—

The design for an embroidery, representing a cockatoo, the same consisting of the head A, having the parts a b, of the body B, having the parts d e f g h i, and of the tail C, substantially as shown.

HENRY BOSSHARDT.
